TENSION CONTROLLING DEVICE FOR
ROLLING CLOSURESClifford Traut, Newport, Ky., assignor to The
Higgin Manufacturing Company, Newport, Ky.,
a corporation of West Virginia

Application July 29, 1932. Serial No. 625,848

12 Claims. (Cl. 156—39)

My invention relates to the provision of means whereby the tension of the spring roller of rolling closures may be adjusted after the complete installation of the closure. While my invention is applicable to rolling closures of all types, including, but without limitation, rolling light-tight closures and the like, I shall, for purposes of making a complete disclosure, describe it in connection with a rolling window screen, it being understood that this is not a limitation upon my invention. A rolling window screen, as known in the art, comprises generally a housing containing a spring roller, which housing is installed at the top of a window opening. The screen cloth or flexible closure member is wound upon the spring roller, and may be withdrawn from the housing against the tension of the spring through a lengthwise slot in said housing. There are also provided side guide members located along the sides of the window opening, in which the edges of the closure member ride. A draw bar affixed to the lower end of the closure member is also arranged to ride along the guides and serve as a means for withdrawing the closure member from the housing and causing it to cover the window opening.

It is the general practice to adjust the tension of the spring controlling the roller prior to the installation of the screen. Some sort of ratchet device is provided which permits such adjustment. It will be understood also, that in most installations the housing and/or other parts are concealed by the window trim. Even where this is not the case, the nature of the installation is almost always such that the ends of the spring roller housing are not accessible after the installation thereof. Since all commercial installations of which I am aware before this time have been adjustable as to tension only at the ends of the housing, it has not been possible to vary the tension after the installation of the screen or closure and while it is in place. Should the initial adjustment made prior to the installation of the screen be incorrect, or should, for any reason, the tension come out of adjustment, it has hitherto been necessary to demount the entire casing with the disturbance of any portions of the window trim which covered or concealed it. The adjustment of the tension in rolling window screens has therefore involved great inconvenience, time and expense, and is a serious labor item connected with the installation and use of such devices. It is a primary object of my invention to provide mechanism in connection with the spring roller of a rolling closure whereby the

tension may be adjusted after the installation of the closure and without disturbing that installation.

While not restricted thereto, my invention, as set forth herein, has especial utility in connection with rolling closures having spring roller housings of the flush end type. The application of adjustment devices to such housings involves difficult problems for the reason that the adjustment mechanism must be confined to an exceedingly small space, and cannot be either bulky or cumbersome. Moreover, it must be inexpensive to manufacture and install, positive in action, and not liable to maladjustment or deterioration. The solution of these problems constitutes another object of my invention.

Still another object of my invention is the provision of an adjustment means as aforesaid, which does not interfere with the preliminary adjustment of the tension of the spring in the ordinary way. Such adjustment is highly desirable for the reason that to produce substantially the tension desired involves rotating the roller shaft a considerable number of turns, and it would be both slow and inconvenient to attempt to make the entire adjustment by means of an adjustment device, particularly one having a gear ratio mechanism.

These and other objects of my invention which will be set forth hereinafter, or will be apparent to one skilled in the art upon reading these specifications, I accomplish by that certain construction and arrangement of parts of which I shall now describe the aforesaid exemplary embodiment.

The drawings are now referred to, wherein—
Figure 1 is an elevational view of a screen installation with parts thereof in section.

Figure 2 is an end view of the adjustment apparatus with parts shown in section.

Figure 3 is a sectional view taken along the lines 3—3 of Figure 2, showing the same assembly.

Figure 4 is a perspective view of a crown gear device which I prefer to use.

Figure 5 is another end view of a spring roller housing embodying my invention, with a portion of the cover member cut away.

Figure 6 is a view of part of a spring roller showing the method of engagement of the spring end therein.

Figure 7 is a spur gear which I prefer to use.

Figure 8 is a pawl employed in connection with the spur gear of Figure 7.

Figure 9 shows a simple form of spring which controls the pawl of Figure 8.

Briefly in the practice of my invention I provide a gear which non-rotatably engages the end of the spring roller shaft and is covered by a housing member having an extension thereon reaching below the spring roller housing. Another gear meshing with the first is located with respect to this extension so as to be engageable by a tool, such as a screw driver, from the inside of the window opening. I provide a pawl which coacts with said second gear to stop the motion thereof. This pawl is so shaped as to permit motion of said gear in a direction to increase the tension, the pawl under these circumstances moving against a controlling spring. The pawl is arranged positively to stop the motion of the gear in the reverse direction, but means are provided whereby said pawl may be manually depressed to permit such rotation. The problems worked out in connection with the configuration and interaction of these several members will be clear from the description of a specific embodiment which follows.

I have shown in Figure 1 a spring roller housing indicated generally at 1. It is closed upon one end by an end enclosure member 2. This closure member fits over the end of the housing like the lid of a box, and is perforated for the reception of tongues on the housing, which tongues are bent over on the end closure member to hold it in place. The member is also perforated to receive and journal the spring roller shaft 3. The other end of the housing has two interspaced closure members indicated generally at 4 and 5, which are interspaced so that a crown gear arrangement 6 may lie between them. It will also be noted in Figure 1, that the end closure members 4 and 5 have extensions below the roller housing, between which extensions a spur gear 7 is located. This gear meshes with the gear 6, and may be engaged by a screw-driver 8 so that the crown gear 6 may be turned thereby.

Portions of the crown gear 6 hereinafter to be described, non-rotatably engage the end of the shaft 3, and form a bearing therefor with respect to the end closure member 4. The flattened end of the shaft 3 may be engaged by a handle or crank 9, which will pass through a perforation in the outer closure member 5. The shaft may thus be directly rotated by means of this handle.

Surrounding the shaft 3 is a roller member 10 of tubular form, having bushings 11 and 12 respectively, at the ends thereof, whereby the roller is rotatively mounted upon the shaft 3. A coiled spring 13 surrounds the shaft and is engaged therewith at the left hand end in Figure 1 as at 14. At the right hand end, as at 15, this spring is engaged with the roller. The screen or closure cloth 16 is wound on the roller. It will be clear that in the operation of the screen, so long as the gear 6 holds the shaft 3 non-rotatively, the roller 10 may rotate with respect to the shaft with or against the tension of the spring 13, whereby the closure cloth may be drawn into the housing or withdrawn therefrom.

Referring now to Figures 2 to 9 inclusive, for a more particular description of the elements of this assembly, it will be seen that the inner closure member 4 is perforated as at 4a (Figure 3). The gear 6 has attached thereto, either directly or with an intermediate ring 17, a flanged socket-like member 18. The edges of this member and/or the ring 17 fit into the perforation 4a and form in part the bearing for the right hand end of the shaft hereinabove described. The end of the shaft is flattened as at 3a, and

the member 18 is slotted, as clearly shown in Figure 2, to receive the flattened end of said shaft.

I prefer to make the gear 6 in the form of a crown gear by a stamping operation. The gear thus comprises a disc-like portion 6a and a series of teeth 6b extending substantially at right angles thereto. This construction is important, as will hereinafter be shown, for the purpose of maintaining at all times a positive interengagement of the gears 6 and 7. 85

Referring again to Figure 3, it will be seen that the inner closure member 4 (which, as at 4b, may be recessed so as to extend partly within the end of the housing member 1, and thus save some space) is perforated as at 4c to receive the hub portion 7a of the gear 7. This gear is shown more clearly in Figure 7. It may be cheaply made by a stamping operation, and comprises the hub or boss 7a which projects from one side. It also has a series of rather large teeth 7b projecting from the edges thereof. The boss 7a is slotted as at 7c for the reception of the screw-driver 8. The boss portion 7a of the gear 7 is journaled in the perforation 4c. 90 95

The outer cover portion, indicated generally at 5, has flanges 5a adapted to fit over the end of the screen roller housing 1, and is also perforated in the usual manner for the reception of the tongues 19 on the housing, which are bent over to fasten the cover member in place. When in place, as clearly shown in Figures 1 and 3, the outer cover member 5 will be interspaced from the inner cover member 4 by a distance substantially equal to the thickness of the crown gear 6. 100 105 110 It also has an extension 5d dropping below the screen roller housing and cooperating with the extension 4b on the inner closure member 4 to hold the gear 7 in place. The tongues 19, in co-operation with the screen roller housing, will hold the two end closure members in proper position in their upper portions. The lower portion of the two members come together by reason of an offset 4e in the inner closure member, and may, if desired, be fastened together by screws 120 or bolts 20. The two members are likewise perforated as at 21 for the reception of a wood screw or the like 22 (Figure 1), whereby this portion of the device may be held to the side of the window frame. 125

The outer closure member 5 is perforated as at 5c so that the crank 9 may be directly engaged with the shaft portion 3a. It also may have depressed portions, indicated at 5b, for the purpose of assisting in maintaining the position of the 130 gear 6.

The interaction of the two gears and the way in which they are maintained in continuous engagement will now be clear. As aforesaid, the teeth 7b on the gear 7 are quite large and are long enough so that one of them at least, at all times engages the teeth 6b and extends within the gear 6 lying against the disc portion 6a thereof. The spring 13 engaged, as at 14, with a shaft at one end and at the other (as shown in Figure 6) having a reversely bent portion 23 hooked into an L-shaped slot 24 in the roller 10, acts to urge the shaft 3 to the right in Figure 1, and tends to maintain the relationship of the gear 6 to the 145 end housing member 5. The teeth of the gear 7 are thus at all times caught between the end housing 5 and the disc portion 6a of the gear 6; and the gears, while very thin, cannot come out of interengagement. In this way I have secured 150

- a positive interengagement of gears in an exceedingly thin space.
- I next provide a pawl member, shown in Figure 3, and comprising a body 25 having a handle portion 25a and an engagement tooth 25b. The handle portion 25a extends through a slot 26 in the inner closure member 4, and the body and tooth, as shown, lie between the extensions of the closure members 4 and 5. The pawl is shown in Figure 2 in a position of engagement with teeth 7b of the gear 7. The spring 27 of Figure 9 has reversely bent ends 27a and 27b. The portion 27a may be engaged in a socket member 28 spot-welded or otherwise attached to the inner closure member 4. The other reversely bent portion 27b of the spring may be engaged in a hole 25c in the pawl member. When the assembly is as shown in Figure 2, the action of this spring will be to urge the pawl toward the left. Should a repair or replacement of the spring be found desirable, it may be disengaged from the pawl 25 by moving its lower end to the right in Figure 2, after which it may be swung up as shown in dotted lines in Figure 3, and disengaged from the socket member 28. A new spring may be installed by a reversal of these operations. The pawl is shown in Figure 5 in a position in which it frees the gear 7. This position may be attained by pressing manually upon the handle portion 25a, or may be forced by a clockwise rotation of the gear 7, as shown in that figure. The parts are so adjusted, however, that a clockwise rotation of the gear 7, as shown in Figure 5, is in a direction against the tension of the spring 13. Hence, prior to installation the handle 9 may be directly engaged with the flattened end 3a of the roller shaft, and as much tension as is desirable in the opinion of the operator may be placed upon the spring by a direct and speedy operation. The tension may be released by depressing the pawl to the position shown in Figure 5. If a screw-driver is first engaged in the perforation 7c, the release of tension may be controlled as desired. Otherwise, when the gear 7 is released, both gears will rotate under the influence of the spring 13 to relieve substantially the entire tension. The way in which tension may be adjusted after the installation of the screen will be clear from Figure 1 and the foregoing explanation.
- Various modifications may be made in my invention without departing from the spirit thereof.
- Having thus described my invention, what I claim as new and desire to secure by Letters Patent, is:—
1. In a device for rolling closures, the combination of a spring roller and shaft, a housing therefor, a pair of spaced closure members for one end of said housing, said closure members having extensions beyond the line of a wall of said housing, and means for varying the tension of said spring roller located between said spaced end closure member and accessible for operation through one of said extensions.
  2. In a device for rolling closures, the combination of a spring roller and shaft, a housing therefor, a pair of spaced closure members for one end of said housing, said closure members having extensions beyond the line of a wall of said housing, means for varying the tension of said spring roller located between said spaced end closure member and accessible for operation through one of said extensions, said mechanism comprising a gear having an operative connection to said shaft, and a second gear meshing
  3. In a device for rolling closures, the combination of a spring roller and shaft, a housing therefor, a pair of spaced closure members for one end of said housing, said closure members having extensions beyond the line of a wall of said housing, means for varying the tension of said spring roller located between said spaced end closure members and accessible for operation through one of said extensions, said means comprising a gear having an operative connection to said shaft, a second gear meshing therewith and having a portion accessible through said extension, and a resiliently mounted pawl means serving as a lock against release of tension.
  4. In a device for rolling closures, the combination of a spring roller and shaft, a housing therefor, a pair of spaced closure members for one end of said housing, said closure members having extensions beyond the line of a wall of said housing, means for varying the tension of said spring roller located between said spaced end closure member and accessible for operation through one of said extensions, said means comprising a gear having an operative connection to said shaft, a second gear meshing therewith and having a portion accessible through said extension, resiliently mounted pawl means serving as a lock against release of tension, said shaft having means for direct engagement by a tool for rotation in a direction permitted by said pawl to tighten the tension of said spring roller the outer one of said closure members being cut away to permit said engagement.
  5. In a device for rolling closures, the combination of a spring roller and shaft, a housing therefor, a pair of spaced closure members for one end of said housing, said closure members having extensions beyond the line of a wall of said housing, means for varying the tension of said spring roller located between said spaced end closure member and accessible for operation through one of said extensions, said means comprising a gear having an operative connection to said shaft, a second gear meshing therewith and having a portion accessible through said extension, resiliently mounted pawl means serving as a lock against release of tension, said shaft having means for direct engagement by a tool for rotation in a direction permitted by said pawl to tighten the tension of said spring roller, said pawl being releasable to permit rotation of said shaft in untensioning direction. The outer one of said closure members being cut away to permit said engagement.
  6. In a rolling closure, the combination of a spring roller and shaft, a housing therefor, and spaced end closure members for one end of said housing, a gear of the crown type operatively connected to said shaft, and a second gear of the spur type having teeth meshing with the teeth of said crown gear, the meshing teeth of said spur gear being confined between a disc-like portion of said crown gear and one of said end closure members.
  7. In a rolling closure, the combination of a spring roller and shaft, a housing therefor, and spaced end closure members for one end of said housing, a gear of the crown type operatively connected to said shaft, and a second gear of the spur type having teeth meshing with the teeth of said crown gear, the meshing teeth of said spur gear being confined between a disc-like portion of said crown gear and one of said end closure members.

members, at least one of said end closure members having an extension beyond the plane of a wall of said housing, said spur gear being mounted to said extension and accessible from 5 beyond a side wall of said housing for manual rotation.

8. In a rolling closure, the combination of a spring roller and shaft, a housing therefor, and spaced end closure members for one end of said 10 housing, a gear of the crown type operatively connected to said shaft, and a second gear of the spur type having teeth meshing with the teeth of said crown gear, the meshing teeth of said spur gear being confined between a disc-like portion 15 of said crown gear and one of said end closure members, at least one of said end closure members having an extension beyond the plane of a wall of said housing, said spur gear being mounted to said extension and accessible from beyond 20 a side wall of said housing for manual rotation, and a pawl mounted with respect to said extension and engaging teeth of said spur gear to serve as a lock against release of tension.

9. In a rolling closure, a spring roller and shaft, 25 a housing and a pair of spaced end closure members upon one end thereof, a crown gear mounted for rotation between said end closure members, means on said end closure members to maintain said gear in alignment, an operative connection 30 between said gear and said shaft, said outer closure member having a perforation whereby a tool may be directly engaged with said shaft, and means accessible from beyond the side wall of said housing to rotate said gear.

35 10. In a rolling closure, a spring roller and shaft, a housing and a pair of spaced end closure members upon one end thereof, a crown gear mounted for rotation between said end closure members, means on said end closure members, 40 to maintain said gear in alignment, an operative connection between said gear and said shaft, said outer closure member having a perforation whereby a tool may be directly engaged with said shaft, means accessible from beyond the side wall 45 of said housing to rotate said gear, said means

comprising a spur gear having teeth meshing with the teeth of said crown gear and confined between the disc portion of said crown gear and one of said end closure members, and means for urging said crown gear toward said end closure member. 80

11. In a rolling closure, the combination of a spring roller and shaft, a housing therefor, end closure members for said housing of the flush type, a supplementary end closure member spaced 85 from one of said end closure members slightly toward the center of said housing, said last mentioned end closure members having extensions beyond a side wall of said housing, a gear located between said last mentioned end closure members and having a mounting portion extending through the inner of said members, said mounting portion having an operative connection with said shaft, a second gear having teeth meshing with the teeth of said first gear and located in 90 part at least between the extensions of said members, the inner member having a perforation and said second gear having a mounting portion extending through said perforation, and having means whereby it may be engaged by a tool, said 100 inner closure member having another perforation, a pawl having a portion located between said extensions and engaging the teeth of said gear and another portion extending through said last mentioned perforation for manual operation, and a spring urging said pawl into locking engagement with the teeth of said gear. 105

12. In a rolling closure, the combination of a spring roller and shaft, a housing therefor, spaced closure members upon one end of said housing 110 and having extensions beyond a side wall thereof, substantially coplanar gears located between said end closure members, one of said gears having an operative connection with said shaft, the other of said gears being accessible for operation from beyond 115 the side wall of said housing, and ratchet means for normally preventing the rotation of said gears in un-tensioning direction. 115
